STITCH ADJUSTER FOR SEWING MACHINES

Hermon H. Woodward, Troy, and Alpha H. Wright, Albany, N. Y., assignors to Hall, Hartwell & Co., Inc., Troy, N. Y., a corporation of New York

Application January 5, 1932, Serial No. 584,858

11 Claims. (Cl. 112—210)

Our invention consists in an improved form of stop for the adjuster having a fixed notch.

In the accompanying drawing we have shown one form of our invention, wherein

5 Fig. 1 is a perspective view of a sewing machine, provided with our new adjuster;

Fig. 2 is a front view of the machine, partly in section, showing in detail the application of our device thereto;

10 Figs. 3 and 4 show our adjuster under different conditions.

It is at present the standard practice to adjust for length of a sewing machine stitch by connecting the outer end of the regulating lever

15 to different points on the frame of the machine by means of a clamp operated by a thumb screw. This clamp, together with the end of said regulating lever, is moved up or down, according to the desired length of stitch, and, at the proper

20 point, the clamp is fastened to the machine frame by tightening the thumb screw down solidly against the side of the machine. In this old mode, a change of adjustment requires that the clamp be loosened by releasing the thumb screw, 25 and its new position ascertained by experiment before reclamping it. That takes time and careful attention.

It is also difficult to fix the adjustment always at exactly the same point, in order to give the 30 same length of stitch that was secured by a previous adjustment. A manufacturer, making superior goods and particular about uniformity of stitch, finds this objectionable. It also requires care and takes time, which should not be lost. 35 Moreover, the adjustment is in the control of the operative, who is tempted to make the stitch too long, that is, fewer to the inch, whereby she can make more money.

In some cases the manufacturer has plugged 40 the adjuster at a certain point for a fixed number of stitches per inch. That is not desirable, because different machines cannot be plugged at the same point for a given length of stitch. Also, a plugged machine, when it becomes worn, will 45 cease to maintain the desired length of stitch and for machines requiring frequent changes in the length of stitch, plugging is not available.

The purpose of our invention is a device that 50 makes changes of stitch-length more quick, certain and easy than heretofore and also accurate for two different lengths, for instance, one length for the "running" operation and another for the "stitching down" operation. The machine can then only operate at those two lengths of stitch. 55

This adjuster cannot be readily tampered with,

because it requires for its manipulation a special wrench. It is also independent of wear in the feeding mechanism and requires much less supervision of the operatives.

Thus, a cuff is usually constructed of three plies of material, a facing, an interlining and a backing. The interlining, and sometimes, also, the backing, are first applied to the end of the sleeve, and this may be done by a long stitch, because this seam is hidden from view in the finished garment. This is called "running". But when the edge of the facing is turned over and the three plies, together with the sleeve, are to be stitched together, the resulting seam will be visible in the finished article, so it must be made with a short stitch. That is called "stitching down". Both "running" and "stitching down" are performed by one operator who also makes the adjustment changes for the two different lengths of stitch.

20 Referring to the drawing, Fig. 2 shows one well known form of stitch adjustment mechanism. In this Fig. 2 F represents the main horizontal shaft of the machine; E is a cam on said shaft which oscillates a fork G on rod H and said rod H is connected by a bell crank J to the left hand end of the feed member K. These elements serve to give a forward and backward movement to the feed member K. The right-hand end of feed member K contains a slot in which rides a roller 30 on the end of lever L and lever L, by means of lever M, is worked up and down through the agency of rod I leading up to a cam on the aforesaid main shaft F.

O is the stitch adjuster or regulator. It is 35 a lever which is oscillated around its fixed center P to provide for changes in the length of fabric feed per stitch. The left-hand end of said lever O is connected by link Q to the fork G aforesaid. Lever L aforesaid acts to raise the feed member up and down, while lever J works it forward and back as just described.

40 Thereby the feeding teeth on the top surface of feeding member K are first raised slightly to engage the fabric then moved leftward the distance of a stitch, then drawn downward from the fabric, and returned back clear of the fabric to its starting point at its lower level. The length of the stitch thus made may be increased or diminished by working the regulator lever O, and 45 thereby changing the angle of the link Q. The mechanism above described constitutes no part of our present invention, being old and standard and here shown merely for illustration.

50 Our invention herein relates to the control of

20

the said regulator lever O to give its right-hand end an exactly determined position with respect to the frame or casing R of the machine. For this purpose we enter a screw S into the end 5 of lever O and the outer end of said screw S is extended through a slot in the casing R and jointed to the top of a vertical rod B outside of the casing. A spring W surrounds the lower end of this rod B and reacts against a bracket 10 V fixed on the casing R to press the rod B downward. This spring is sufficiently strong to prevent oscillation of the feed. There is a toe C projecting out from the rod B near the lower end thereof, and secured to said rod by nuts T. 15 The said spring W bears at its lower end against the top of said nuts T and thereby tends to force the rod B constantly downward and to also force down with rod B the outer end of the aforesaid regulator lever O which is jointed to B. 20 If the said toe C on the lower end of rod B does not encounter any stop the spring W will force it, and also the rod B to which it is attached, clear down and so pull the outer right-hand end of the regulator lever O down to its 25 limit, that is, down till it strikes the bottom edge of the slot in casing R through which the outer end of lever O protrudes or till the lower end of rod B strikes the floor of the frame R at e as shown in Fig. 4. Another stop for rod B is provided by a pivoted plate D, pressed up by a spring 30 U. This plate D has a notch in its upper left-hand corner, and a projection or handle a. The spring U normally tends to move the plate D to the position shown in Figure 3, but by means 35 of the handle a said plate may be tilted against the tension of said spring, to the position illustrated in Figure 4. While said plate is tilted to the latter position, the toe C is permitted to pass by the notch b till the lower end of rod B strikes the floor of the frame R as shown in Fig. 4.

Moreover, by means of a special wrench, the nuts T T can be set up or down to shift the position of the toe C with relation to rod B in order 45 to compensate for wear. Such compensation is only required at rare intervals and are made by the inspector while the changes which the operative can make are easy, simple and accurate. They are of a different class from those requiring the attention of the inspector. By screwing 50 the nut Y down on the rod B so that the member V would act as a stop, it is possible to obtain a considerable intermediate variation in the number of stitches per inch within the range 55 determined by previous adjustments of the nuts T relative to the stop V. Upon adjustment of the nuts T, the distance of the lower end of rod B from the base R may be varied when the member C engages stop b.

By the above-described device the adjustment 60 which the operative needs to make may be set, instantly, positively and accurately to any one of two or more positions, without the need of screwing down a clamp to get a frictional grip on which the adjustment depends, as in the previous art.

What we claim as new and desire to secure by Letters Patent is:—

1. A stitch-length adjuster for sewing machines comprising a movably supported stitch regulator, a rod connected at one end with an end of said stitch regulator, a fixed abutment positioned to engage the other end of said rod, and controllable abutment means positioned to

engage and maintain said other end of the rod at a location spaced from said fixed abutment.

2. A stitch-length adjuster for sewing machines comprising a movably supported stitch regulator, a rod connected at one end with an end of said stitch regulator, a fixed abutment positioned to engage the other end of said rod, and a movable member having an abutment portion positioned to maintain said other end of the rod at a location spaced from said fixed abutment. 10

3. A stitch-length adjuster for sewing machines comprising a movably supported stitch regulator, a rod connected at one end to and depending from an end of the stitch regulator, a fixed abutment positioned to engage the lower end of said rod, a controllable abutment positioned to maintain the lower end of the rod at a location spaced from the fixed abutment, and a spring acting normally to press said rod downwardly so as to prevent feed oscillation acting upon said adjuster member. 20

4. A stitch-length adjuster for sewing machines comprising a movably supported stitch regulator, a rod connected to and depending from said regulator, a fixed abutment positioned to engage the lower end of said rod, a spring acting normally to move said rod toward said fixed abutment, and a tiltable member supported adjacent to said fixed abutment and having a second abutment so positioned as to maintain the lower end of said rod at a location spaced from said fixed abutment. 25

5. A stitch-length adjuster for sewing machines comprising a pivoted stitch regulator, a spring pressed rod connected at one end with said regulator and depending therefrom, a fixed abutment positioned to engage the lower end of said rod, and a spring pressed controllable abutment member having an abutment portion positioned to engage and maintain the lower end of the rod at a location spaced from said fixed abutment. 30

6. A stitch-length adjuster for sewing machines comprising a movably supported stitch regulator, a spring pressed rod connected at one end to said regulator and depending therefrom, a fixed abutment portion positioned to engage the lower end of said rod, an abutment toe carried by said rod and spaced from the lower end thereof, and other controllable abutment means complementary to said toe. 45

7. A stitch-length adjuster for sewing machines comprising a pivoted stitch regulator, a spring pressed rod connected at one end with said regulator and depending therefrom, a fixed abutment positioned to engage the lower end of said rod, an abutment toe movably mounted on said rod, means for adjustably maintaining said toe in spaced relation with respect to the lower end of said rod, and other controllable abutment means complementary to said toe. 55

8. A stitch-length adjuster for sewing machines comprising a pivoted stitch regulator, a rod pivotally connected at one end to an end of the regulator and depending therefrom, and means for maintaining said regulator in adjusted positions, said means being constructed and arranged to engage the lower portion of said rod. 65

9. A stitch-length adjuster for sewing machines comprising a pivoted regulator, a rod pivoted at one end to said regulator and depending therefrom, a fixed abutment member positioned to engage the lower end of said rod, an abutment toe mounted on the lower portion of said rod, a 70

75

- fixed abutment engaging said rod, a spring interposed between said toe and the last-mentioned fixed abutment, and other controllable abutment means complemental to said toe.
- 5 10. A stitch-length adjuster for sewing machines comprising a pivoted regulator, a rod pivoted at one end to said regulator and depending therefrom, a fixed abutment member positioned to engage the lower end of said rod, an abutment 10 toe mounted on the lower portion of said rod, a fixed abutment engaging said rod, a spring interposed between said toe and the last mentioned fixed abutment, a finger piece carried by said rod, and a pivoted abutment member having 15 abutment means complemental to said toe.
11. A stitch-length adjuster for sewing ma-

chines comprising a pivotally supported stitch regulator, a rod connected at one end with an end of said stitch regulator and depending therefrom, a spring normally acting to force said rod downwardly, a fixed abutment positioned to engage the lower end of said rod, an abutment toe 5 movably engaging said rod, means for adjusting said abutment toe toward and from the lower end of said rod, a pivoted member mounted adjacent said fixed abutment and provided with 10 an abutment shoulder complemental to said toe, and a spring normally acting to move said pivoted member to a predetermined position.
